ROTARY PUMP

Daniel Murphy, New Castle, Pa.

Application June 24, 1937, Serial No. 150,017

2 Claims. (Cl. 103—113)

My invention relates to rotary pumps, and consists in structural refinements in self-priming pumps. This comprises a continuation in part of application Serial No. 61,933, filed by me on 5 February 1, 1936.

My structure is particularly, although not exclusively, adapted for pumps employed in moving heavy, viscous fluids, such as the "slip" used in the manufacture of certain articles of chinaware and pottery.

The object of the invention is to provide an improved rotary pump which will not become gas-bound—a pump which automatically primes itself when it is set in operation—and a pump 10 which may be readily inspected and cleaned while in service.

In the accompanying drawing a pump, embodying the invention in exemplary way, is illustrated partly in vertical section and partly in side 20 elevation.

The pump consists in a body 1 and a cover-plate 2, secured together by bolts 3, and forming an involute pump-chamber 4 of usual sort. A shaft 5 supports a vaned impeller 6 in the chamber 4. Within a cylindrical portion 1a of the pump-body 1, the shaft is supported in a bearing of the structure particularly described and claimed in my co-pending patent application, Serial No. 138,806, filed April 24, 1937, now Patent 25 No. 2,128,496, dated August 30, 1938, the shaft extending through and projecting from such bearing (as indicated at 5a), is connected to a motor or other suitable driving means (not shown).

The impeller 6 may be of known construction, including a discular body portion 6a carrying a plurality of vanes 6b, but advantageously it is of the refined construction illustrated and described in patent application Serial No. 144,136, filed by 35 me on May 22, 1937, now Patent No. 2,165,808, dated July 11, 1939. The pump-body includes an inlet passage 7, extending from above the pump-chamber 4 downward and opening centrally of the group of impeller-vanes 6b through the side 40 wall of such chamber. And in usual way an outlet passage 8 opens tangentially through the peripheral wall of the chamber, and extends upward from the impeller. During pump operation, the rapidly rotating impeller operates to 45 draw liquid inward through passage 7 into the usual spaces between the vanes of the impeller, whence centrifugal force urges the liquid radially outward and into the outlet passage 8.

The right-hand edges of the impeller vanes 50 6b, as viewed in the drawing, cooperate with the

right-hand side wall of the chamber 4. In service there is wear between these relatively moving parts. As described in my above-noted Patent No. 2,128,496, I embody in the said side wall of the impeller-chamber a wearing ring 21 and the central opening 1a of such ring provides the essential communication between the inlet passage 7 and the chamber 4. Advantageously, the ring 21 is made of material softer than the vanes of the impeller—specifically, the impeller being formed of cast iron or steel, the ring is made of brass or bronze. As to the matter of axial adjustment of the impeller and the replacement of worn parts, reference is again made to said Patent No. 2,128,496.

The liquid entering the pump is drawn upward through a conduit 31 from a source of supply. Above the conduit 31, and at higher elevation than the impeller-chamber 4, I provide a chamber 33 including a check-valve 32 adapted to engage a seat 43. The chamber 33 is closed from above by a cover 30, held in place by means of a removable clamp 29, and the cover carries a spider 36 that extends downward into the check-valve chamber and loosely engages the upper end 20 of a stem 35 integral with the check-valve. The wall of the chamber 33 is formed with plurality 25 of vertical ribs 34; and these ribs, together with the sliding engagement of the stem 35 in spider 36, provide effective means for guiding the valve 32 in its vertical movement to and from the seat 43.

The inlet passage 7 opens laterally into the cylinder 33, and extends downward therefrom to the impeller-chamber 4. The discharge line or 35 passage 8 includes a relatively large receiver chamber 37, and it will be perceived that the receiver chamber is located at higher elevation than the impeller-chamber 4. The check-valve chamber is assembled with the receiver chamber 40 in a flange-union 28, and the assembly of these two chambers is removable as a unit from the pump-body 1, 2. The detachable union is indicated by the reference numerals 27 and 39. The value of this structural feature will later appear.

On the pump side of the check-valve 32, and at a point above such check-valve, a by-pass 38 of relatively small cross section opens through the side wall of the check-valve chamber 33. This by-pass extends to, and opens into, the bottom region of receiver chamber 37. When the impeller is set in rotation and comes up to speed, fluid is drawn upward through conduit 31; the upwardly flowing fluid lifts and holds the valve 32 from its seat, and any air or other gas which 50 55

is trapped above the valve, or rises with the liquid in conduit 31, is by-passed under its own buoyancy through vent 38 into the receiver chamber 37, it being understood that the inlet and outlet passages 7 and 8 are normally filled with liquid, whether the pump be idle or running, to a level substantially above the impeller-chamber 4. It will be noted that in the circumferential intervals between the ribs 34 there is clearance 10 between the wall of the chamber 33 and the periphery of the check-valve 32, and, by virtue of such clearance, the rise of the check-valve to a position against the lower end of the spider 36 does not prevent the escape of gas between the inlet passage 31, 7 and the vent 38. The gas rises through the clearance between the ribs, and escapes through vent 38. When the pump attains its normal operating speed, the entrained gas is drawn into the impeller-chamber and discharged with the liquid being pumped.

In the installation illustrated in this case, the pump is organized above the source of liquid being pumped, and it is in such installations, as those in the art well known, that rotary pumps tend to become gas bound and require priming. A pump of the construction described herein need never be primed, once it has been installed and operated, and, additionally, the pump will never become gas bound.

30 In case the pump be arranged below the level of the source of liquid, these particular problems do not exist, and the check-valve structure and receiver-chamber are not needed. In adapting the pump to either of these conditions of service, the check-valve and receiver-chamber are, as already mentioned, provided in a unitary structure that may be readily detached from the pump proper, by removing the bolts 39. That is, the unit 33, 37 may be readily assembled with or 35 removed from the pump, to meet one condition of service or the other.

It is also noteworthy that, by virtue of my structure, the pump proper and bearing unit may be readily removed from an installation in the 45 field, and a new unit quickly installed. Thus, if there should be bearing or impeller failure, the time lost is only a matter of a few minutes.

It is important that the check-valve assembly 33, 32 and by-pass 38 may be readily inspected 50 and cleaned. To such end the cover 30 and check-valve 32 are adapted to be removed. It is merely necessary to remove the clamp 29, lift the cover 30, and withdraw the valve 32, it being noted that the upper end of the valve-stem 35 55 is accessible to the grasp of the attendant. In the wall of the check-valve chamber, opposite to and in line with the by-pass 38, I provide a plug 40. By removing this plug, a wire or other suitable instrument may be used to clean the 60 by-pass.

I have found that to obtain best operation, the size (cross-section) of the by-pass 38, while being of relatively small cross-sectional area in any case, must be minutely determined for each field 65 of service. When pumping heavy liquids, the by-pass should be larger than when pumping light liquids. In order to obtain the desired variability in the otherwise fixed size of the by-pass 38, I provide in the plane of meeting of the flanges 28 (either in the body of the receiver-

chamber 37 or in the body of the check-valve chamber 33) a block 41, including an orifice 42 of proper size.

To the ends in view it is important to note in addition to what already has been said that the check-valve 32 is arranged within a cylindrical chamber 33; that the by-pass is of relatively small cross-sectional area; that the by-pass, extending from the receiver-chamber 37, 10 opens in the cylindrical wall of the check-valve 10 chamber at a point above the check-valve therein and above the mouth of the inlet passage 7 that opens into the check-valve chamber; that the by-pass is normally always open, so that gas may 15 flow into the receiver-chamber, or liquid may flow from the receiver-chamber into the inlet passage 7 of the pump; and that the cylindrical wall of the check-valve chamber continues upward a substantial interval above the point where the by-pass opens into the check-valve chamber. 20

By virtue of my construction the check-valve chamber may be opened, the check-valve removed and cleaned, and the by-pass cleansed, without interrupting operation of the pump. And by removing the usual drain-plug 9, all chambers and passages of the pump may be entirely drained.

Modifications and refinements of the invention are permissible, within the terms and intent of the appended claims.

I claim as my invention:

1. In a pump including a pump body, an impeller chamber in said body, a rotary impeller in said chamber, an inlet passage leading to the chamber, an outlet passage leading from the chamber, and a check-valve unit including an inlet and an outlet, a check-valve in the line of flow between such inlet and outlet, a by-pass opening into said check-valve unit above the check-valve therein; and a removable closure arranged to give access to said by-pass for cleaning while the pump is in operation; the improvement herein described in the above-defined organization that consists in a detachable member interconnecting the pump and the check-valve unit, said member including a passageway connecting said inlet passage of the pump to said outlet of the check-valve unit, said member including a passageway leading from said outlet passage to the pump, and a passage leading from the by-pass from the check-valve chamber to said last-mentioned passageway. 30

2. In a pump including a pump body, an impeller chamber in said body, a rotary impeller in said chamber, an inlet passage leading to the chamber, an outlet passage leading from the chamber, and a check-valve unit including an inlet and an outlet, a check-valve in the line of flow between such inlet and outlet, and a by-pass opening into said check-valve unit above the check-valve therein; the herein described improvement in the above-defined organization that consists in a detachable receiver-unit interconnecting the pump and the check-valve unit, said receiver-unit including a passageway connecting said inlet passage of the pump to said outlet of the check-valve unit, and a passageway leading from said outlet passage of the pump, together with a passageway establishing communication between the last-mentioned passageway and the by-pass of said check-valve unit. 55

CERTIFICATE OF CORRECTION.

Patent No. 2,179,858.

November 11, 1939.

DANIEL MURPHY.

It is hereby certified that error appears in the printed specification of the above numbered patent requiring correction as follows: Page 2, second column, line 49, claim 1, for the words "passage to" read passage of; and that the said Letters Patent should be read with this correction therein that the same may conform to the record of the case in the Patent Office.

Signed and sealed this 12th day of December, A. D. 1939.
